UNITED STATES PATENT OFFICE.

WALTER B. MEHL, OF WALTHAM, MASSACHUSETTS, ASSIGNOR TO E. HOWARD WATCH COMPANY, OF WALTHAM, MASSACHUSETTS, A CORPORATION OF NEW JERSEY.

WATCH-MOVEMENT.

No. 900,183.

Specification of Letters Patent.

Patented Oct. 6, 1908.

Application filed February 29, 1908. Serial No. 418,466.

To all whom it may concern:

Be it known that I, WALTER B. MEHL, a citizen of the United States, and a resident of Waltham, in the county of Middlesex and 5 State of Massachusetts, have made and invented certain new and useful Improvements in Watch-Movements, of which the following is a specification.

My invention relates to an improvement 10 in stem winding and setting watches, and more particularly to the winding and setting mechanism of the lever-set type, the object being to provide mechanism of this character which will consist of but few parts, 15 which will be simple in its construction, and positive in its operation, and in which the various parts will be retained in either their winding or setting positions until moved therefrom by a manual operation.

20 Another object of my invention is to provide a movement plate for a watch of this character having its front or dial side recessed to receive parts of my improved lever-set mechanism, and its opposite or train side 25 adapted to receive parts of the pendant setting and winding mechanism shown and described in Letters Patent of the United States, issued August 1st, 1905, to Ryland L. Taft, assignor, and numbered 796,162, the 30 winding pinion, winding arbor, and the sliding clutch or toothed-sleeve, shown in said patent, being common to both constructions.

The purpose is to provide a movement 35 plate which may be made in large quantities and which may be employed in either the lever-set or pendant-set type of watch, thereby avoiding the necessity of making two styles of movement plates.

40 A further purpose of this peculiar construction is to provide a watch in which the winding and setting mechanism may be quickly and easily changed from one type to the other, if for any reason, such a change is desired.

45 With these and other objects in view, my invention consists in certain novel features of construction and combinations of parts, as will be hereinafter fully described and pointed out in the claims.

50 In the accompanying drawings Figure 1 is a view of a part of the watch movement constructed in accordance with my invention

and showing the several parts in the setting position. Fig. 2 is a similar view, the parts being shown in the winding position. Fig. 3 55 is a vertical sectional view taken on the dotted line shown in Fig. 1. Fig. 4 is a front plan view of the movement plate, and Fig. 5 is a rear plan view of the same.

Referring to the drawings, A represents 60 the watch case center, B the movement plate, C the pendant and D the crown secured to the outer end of the pin or stem d, the opposite or inner end of which engages with the upper end of the winding arbor F. Slidably 65 mounted upon the squared portion of the winding arbor F is a clutch or toothed sleeve I, provided at its upper end with teeth i¹ normally engaging the winding pinion K, rotatably mounted upon the winding arbor F, as 70 shown in Fig. 3, and provided at its lower or inner end with crown teeth i² adapted to be moved into engagement with the intermediate setting wheel i³, as shown in Fig. 1, when it is desired to set the watch, in the manner 75 hereinafter described. Intermediately of its upper and lower ends, the clutch or toothed sleeve I is provided with a groove or recess i for the purpose hereinafter set forth. The foregoing construction and arrangement of 80 parts is fully shown and described in the patent of Taft, referred to above, and are common to both the pendant-set mechanism, shown therein, and my improved lever-set 85 mechanism, which I will now describe.

Pivoted upon the outer or dial side of the movement plate B, and lying within a suitable recess or depression E formed therein, is a lever G, the longer arm g¹ of which is provided with an outwardly extending end 90 portion g² adapted to pass through a notch or recess a formed in the watch case center and communicating with the recess E, and being provided with the usual projection or finger piece b, by means of which the lever 95 G may be moved outward or inward as desired. The shorter arm g³ of the lever G, which is preferably beveled as shown, engages with and is retained in its normal position (shown in Fig. 2), by the free end h of 100 the spring H, which is secured to the plate B within a suitable recess L which communicates with the recess E.

The lever G is provided with a depending

arm *c*, which is preferably slightly curved, and which is adapted to co-act with the upwardly extending free end *m* of the lever *M*, pivoted in the recess *L*, which lever carries 5 a pin *n* engaging within the recess *i* of the clutch or sleeve *I*, whereby any movement of said lever will cause a corresponding movement of the clutch or sleeve. This clutch lever *M* is supported at one end by 10 the pivot screw *L*² passing through the opening *L*¹ formed through the plate *B*, this opening *L*¹ being so located as to accommodate the clutch lever of either the pendant or lever set mechanism. The free end *k* of the 15 spring *H* tends to hold the lever *M* in its normal or upper position, as shown in Fig. 2, whereby the teeth *i*¹ of the clutch or sleeve *I*, are normally held in engagement with the winding pinion *K*, and when the parts are 20 so positioned the watch may be wound by rotating the crown in the usual manner.

When it is desired to set the watch, the lever *G* is moved outwardly by means of the finger piece *b*, the depending arm *c* moving 25 upwardly and exerting a cam - like action upon the upwardly extending end *m* of the lever *M*, whereby the latter is forced downward against the action of the free end *k* of the spring *H*, into its lower or alternate position, the pin *n* carried thereby, causing the clutch or sleeve *I* to move into its lower position, in which the crown teeth *i*² will be thrown into engagement with the intermediate setting wheel *i*³, as clearly shown in 30 Fig. 1, whereby the watch may be set by rotation of the crown. The arm *c* and the free end *m* are so proportioned that when the parts are in their setting or alternate position, the former will slightly overlap the 35 latter, as shown in Fig. 1, whereby the parts will be securely locked in position. After the watch has been set, the lever *G* is pushed inward, the arm *c* disengaging itself from the free end *m* of the lever *M*, whereby the end 40 *k* of the spring *H* will force said lever and the clutch or sleeve *I* into their normal or upper positions, the end *h* of the spring *H*, co-acting with the beveled end of the short arm *g*³ of the lever *G*, to hold said lever in 45 its normal position, and preventing any accidental movement thereof.

I preferably so form the recesses *E* and *L* that the depths thereof will be the same as the thickness of the levers *G* and *M*, and the 55 spring *H*, in order that, when the parts are secured in place, their upper surfaces will be flush with the upper or outer surface of the movement plate.

It will be seen that I have devised a very 60 simple, but positively acting lever-set mechanism, and the operating levers and spring thereof are located upon the side of the movement plate opposite to that to which the levers and spring of the pendant - set

mechanism in the above-mentioned Taft 65 patent are adapted to be secured, so that the movement plate may be used with watches of either the lever-set or pendant-set type, and a watch of one type may be easily and readily converted into one of the 70 other type.

Having fully described my invention, what I claim as new and desire to secure by Letters Patent, is:—

1. In a stem winding and setting watch, 75 the combination with a movement plate, of an arbor rotatably supported thereby, a clutch slidably mounted upon said arbor, a clutch lever pivoted to said plate for operating the clutch, a manually operated setting 80 lever pivoted to said plate and adapted to move and lock said clutch lever in its setting position, and a spring one end of which holds said setting lever in both its setting and winding positions, and the opposite end of 85 which spring engages and returns said clutch lever to its winding position, substantially as described.

2. In a stem winding and setting watch, 90 the combination with a movement plate, of an arbor rotatably supported thereby, a clutch slidably mounted upon said arbor, a clutch lever pivoted at one end to said plate and free at its opposite end, and provided 95 with clutch engaging means between its free and pivoted ends, and a manually operated setting lever pivoted to said plate and adapted to engage the free end of said clutch lever to lower and lock the same in its setting position, and a spring, one end of which engages and holds the said setting lever in its different positions, and at its opposite end engages and operates to return said clutch lever to 100 its winding position, substantially as described.

3. In a stem winding and setting watch, 105 the combination with a movement plate, of an arbor rotatably supported thereby, a clutch slidably mounted upon said arbor, a clutch lever pivoted at one end and free and curved at its opposite end, and provided 110 with means between its free and pivoted ends for engaging and sliding said clutch, a manually operated setting lever pivoted to said plate and provided with a curved arm extending therefrom, adapted to co-act with the curved end of the clutch lever to lower and lock the same in its setting position, and a spring secured to said plate, and engaging at one end the setting lever to hold the same 115 in its different positions and at its opposite end engaging said clutch lever to return the latter to its winding position when released by said setting lever, substantially as described.

4. In a stem winding and setting watch, a movement plate adapted to receive and hold 120 pendant winding and setting mechanism on

the train side thereof, and recessed on the dial side to receive lever setting mechanism and provided with an opening through the same whereby to pivot the clutch lever of either the pendant setting mechanism on the one side, or lever setting mechanism on the other side, substantially as described.

Signed at Waltham, in the county of Middlesex, and State of Massachusetts, this 26th day of February, A. D. 1908.
